F. H. HARRIS

CORD ANCHOR FIXTURE FOR BINDERS

Filed Nov. 4, 1921

Inventor
FREDERICK H. HARRIS
By: William F. Hale
atty.

UNITED STATES PATENT OFFICE.

FREDERICK H. HARRIS, OF CHICAGO, ILLINOIS, ASSIGNOR TO ALBERT L. BUNCE, OF CHICAGO, ILLINOIS.

CORD-ANCHOR FIXTURE FOR BINDERS.

Application filed November 4, 1921. Serial No. 512,817.

To all whom it may concern:

Be it known that I, FREDERICK H. HARRIS, a citizen of the United States, and a resident of Chicago, in the county of Cook and State of Illinois, have invented certain new and useful Improvements in Cord-Anchor Fixtures for Binders; and I do hereby declare that the following is a full, clear, and exact description thereof, reference being had to the accompanying drawings, and to the characters of reference marked thereon, which form a part of this specification.

This invention relates to improvements in temporary binders of that type in which the papers to be bound are held in place in the binder by a lacing cord that is threaded through binding elements or wings that are hinged to the inner or adjacent margins of the covers and are threaded through the papers, books, or magazines to be bound in the binder, and the invention relates more specifically to fixtures that are fastened to one of the wings and about which the cord ends are wound so as to secure the loose ends of the cords and to maintain the desired binding pressure on the contents of the binder.

The invention consists in the combination and arrangement of the elements shown in the drawings and described in the specification, and is pointed out in the appended claims.

In the drawings:

Figure 1 is a perspective view of a binder equipped with cord holding fixtures embodying my invention.

Figure 2 is a side elevation of one of the fixtures.

Figure 3 is a section on the line 3—3 of Figure 2.

Figure 4 is a perspective view of a modified fixture.

As shown in the drawings, 10, 10 designate the covers of the binder which are connected by the usual flexible center piece or back. 11, 12 designate parallel binding wings or strips which are flexibly connected to the adjacent margins of the covers by the usual fabric hinge portions. The binding wing 11 is provided near its ends with openings 14 through which extend the end portions of the binding cord 15. As herein shown, a single or continuous cord is used, with its intermediate portion lying along the outer side of the wing 11 and with its

ends threaded through the openings 14 to be thence threaded through the contents of the binder and other openings in the wing 12, where they are looped about and anchored to the fixture on the outer side of the wing 12 in the manner hereinafter described.

16, 16 designate fixtures which are fastened to the outer sides of the binding wing 12, one near each end thereof, and about which the ends of the binding cords, after they are threaded through the papers and the said binding wings, are adapted to be looped and to which said cord ends are anchored to maintain binding pressure of the cords on the contents of the binder between the wings and to hold the cord ends from slipping.

The fixture shown in Figures 1, 2, and 3 comprises a flat metal plate 17 which is provided near its ends with openings 18 to receive fastening devices 19 which extend through said plate openings and openings in the wing 12 to fasten the fixture securely thereto. As shown, both said fastening devices consist of hollow rivets or eyelets 20 which are riveted at their ends over the inner side of the wing 12 and the outer side of the plate 17. One of said rivets or eyelets, the outer one, as herein shown, constitutes a cord guide through which the cord 25 extends and in which it is guided.

20 designates a longitudinally disposed, resilient, clamping tongue which lies between the ends of the plate. As shown in Figures 1, 2, and 3, it is formed by metal 30 that is struck up from the plate, and is, therefore, integral at one end with said plate. It is spaced away from the plate at its other or free end a distance to receive therebeneath the free end of the lacing cord. The tongue is rounded at its free end and also at its sides to avoid cutting of the cord, and the terminal of the tongue is curved downwardly. It is preferably provided near its free end with a depression, forming on its under face a rounded projection 35 that constitutes a cord abutment to prevent too ready withdrawal of the cord from under the tongue. The tongue may be stiffened by a longitudinal rib 22.

23 designates a horn near the end of the plate adjacent to the integral end of the tongue. Said horn is made integral with the plate and extends laterally from one side edge thereof in a plane slightly raised

from that of the plate. Said horn is formed on its side edge near the adjacent end of the plate with a recess 24 that is transversely rounded to prevent cutting of the cord.

5 In use, when the cord ends have been threaded through the contents of the binder and through the eyelet 19 at the end of the fixture adjacent to the free end of the tongue, it is carried along the plate at the 10 side of the tongue and is looped over the recessed edge of said horn and is then drawn backwardly and forced between the tongue and the plate in the manner best shown in Figure 2. If desired, the cord may be again 15 looped over the horn and again drawn between the tongue and plate to more securely hold the cord end in place. Usually one loop of the cord about said horn and the gripping action on the cord between the 20 tongue and plate is sufficient to hold the cord end securely in place and to prevent slipping of the cord in the fixture.

In Figure 4 the tongue 25 is shown as made a part separate from the plate 27 and 25 is fastened to said plate by the cord guide eyelet by which one end of the fixture is fixed to the binding wing 12. The free end of the tongue 25 is shown as formed in the same manner as the tongue 20 before de- 30 scribed, and its coaction with the horn 28 to grip the cord end and to hold it from slipping is the same as that shown in the previously described figures.

I claim as my invention:

35 1. A cord anchoring fixture for binders comprising a flat plate having at its ends

apertures to receive fastening devices to fasten the fixture to a support, a resilient clamping tongue connected at one end to, and springable at its other end towards and from the plate, and a horn originating at and extending laterally from the edge of the plate at that end of the fixture away from which the free end of the tongue extends. 45

2. A cord anchoring fixture for binders comprising a flat plate, a resilient clamping tongue connected at one end to, and free from and springable at its other end towards and from, the plate, and a horn rigid with, 50 and extending laterally from a side edge of the plate, with its free end beyond the peripheral outline of said plate at its widest portion, said plate being provided beyond both the connected and the free ends of said 55 tongue with means whereby the fixture may be fixed to a support.

3. A cord anchoring fixture for binders comprising a plate, a resilient clamping tongue connected at one end to, and spring- 60 able at its other end towards and from, the plate, and a horn rigid with, and extending laterally from a side edge and near one end of the plate, said plate being provided at its ends with apertures to receive fastening devices, and hollow fastening and cord guiding rivets to extend through said apertures. 65

In witness whereof I claim the foregoing as my invention, I hereunto append my 70 signature this 28 day of October, 1921.

FREDERICK H. HARRIS.
